UNITED STATES PATENT OFFICE.

INGHAM W. BISBING, OF COLWYN, PENNSYLVANIA.

BEDCOVER-HOLDING DEVICE.

Application filed August 30, 1921. Serial No. 496,829.

To all whom it may concern:

Be it known that I, INGHAM W. BISBING, a citizen of the United States, residing at Colwyn, in the county of Delaware and State 5 of Pennsylvania, have invented certain new and useful Improvements in Bedcover-Holding Devices, of which the following is a specification.

One object of my present invention is to 10 provide an improved device for holding bed covers in their proper positions while on the bed; my improved device being of particular value for use on children's beds or other beds where it is desired to keep the occupant 15 of the bed properly covered.

Another object is to make my improved device of a simple and durable construction and so that it can be readily placed in operative position.

20 These objects, and other advantageous ends which will be described hereinafter, I attain in the following manner, reference being had to the accompanying drawing in which—

25 Figure 1 is a perspective view of a portion of a bed showing my improved devices thereon.

Figure 2 is a fragmentary elevation partly in section showing the manner in which the 30 device serves to hold a bed cover in place, and

Figure 3 is an elevation of certain of the features shown in Figures 1 and 2 illustrating the same detached from a bed.

35 Referring to the drawings, 4 represents the side rails of a bed and 5 represents a top cover which may be an ordinary sheet, blanket or spread.

40 My invention includes a resilient gripper 6 which, as illustrated, can be made of a piece of resilient wire bent into the form clearly shown in Figures 2 and 3; said form including an arcuate portion 7 which preferably extends over an arc of more than 45 180° . This arcuate portion at one end terminates in smooth outwardly turned loops 8 and at the other end is bent downward to provide a yoked portion 9. An elastic member 10, which as illustrated is in the form 50 of an elastic strip, has one end connected to the yoked portion 9 of the resilient gripper 6 and the other end connected to a link 11. A strap 12 extends through the link 9 and

is adapted to embrace the side rail 4 of the bed as clearly shown in Figures 1 and 2. 55 This strap includes an adjusting buckle 13 for a purpose hereinafter described. One or more of these devices may be used on each side of the bed and in Figure 1 I have illustrated two of the devices on each side of the 60 bed. In using the devices for the purpose of holding the cover 5 in its proper position on the bed, the opposite side edge portions of the cover 5 are wrapped around bars 14; said bars preferably being of circular 65 cross section and may be made of wood or other material which is not too easily compressible. The bars 14 form cores or mandrels for the portion of the cover 5 thus wrapped around them. The arcuate portions 7 of the resilient grippers 6 are forced over the wrapped bars so that the wrappings on the bars are held firm against the 70 bars due to the resiliency of the arcuate portions 7 of the grippers 6. The elastic members 10 which extend downward along the side of the bed serve to apply tension to the cover 5 transversely of the bed. At the same time the elastic characteristic of the 75 members 10 allows freedom of movement of a person under the cover 5. The tension of the elastic members 10 can be varied by means of the adjusting buckles 13 on the devices.

80 By the construction above described there are no parts present which would dig into or tear the bed cover and the devices while operative to hold the cover in proper position allow the occupant of the bed to freely move so that the device will not inconvenience the occupant of the bed.

85 While I have described my invention as taking a particular form, it will be understood that the various parts of my invention may be changed without departing from the 90 spirit thereof, and hence I do not limit myself to the precise construction set forth, but consider that I am at liberty to make such changes and alterations as fairly come within the scope of the appended claim.

100 Having thus described my invention, what I claim as new and desire to secure by Letters Patent is:—

A cover-holding device for a bed including a gripper having a resilient arcuate portion; a core member around which the edge

portion of the cover is adapted to be freely wrapped, said core member with the wrappings of the cover thereon being adapted to be resiliently embraced by said arcuate portion of the gripper; and means for securing said gripper to a portion of the bed; substantially as described.

In testimony whereof I have signed my name to this specification in the presence of two subscribing witnesses.

INGHAM W. BISBING.
